UNITED STATES PATENT OFFICE.

FRANK C. LEETHEM, OF MIDDLETOWN, NEW YORK, ASSIGNOR TO LATHAM AUTOMATIC
REGISTERING COMPANY, A CORPORATION OF ILLINOIS.

PRINTER'S FORM.

1,129,579.

Specification of Letters Patent. Patented Feb. 23, 1915.

Application filed April 5, 1913. Serial No. 759,243.

To all whom it may concern:

Be it known that I, FRANK C. LEETHEM, a citizen of the United States, residing at Middletown, State of New York, have invented certain new and useful Improvements in Printers' Forms, of which the following is a clear, full, and exact description.

This invention relates to printers' forms and particularly to an adjustable member 10 which may operate as a hook or clamp or which may be used for other purposes in making up a printer's form.

One of the principal objects of the invention is to provide an arrangement and construction of parts whereby a traveling part such as a plate-engaging-member may have a continuous movement within the form or at least a movement from one guiding member into the next or adjacent member, and 20 at the same time to construct the parts so that the moving part or traveler is self-locking; that is, it holds itself securely in any position into which it is advanced.

In carrying out the invention I prefer to 25 provide the blocks or bases upon which the printing plates are supported in the form, with channels which may be placed end to end. These channels present continuous open slots on their upper sides and further- 30 more they are threaded internally so as to be engaged by a screw which may be rotated from above, and I construct the parts in such a way that this screw can pass uninterrupted from one of these bases to the 35 next.

Although in many instances special alining means for the bases is not necessary, one of the objects of the invention is to provide additional means which may be used where 40 desired to insure a perfectly accurate alinement of the channels.

The invention consists in the general combination of parts and simplicity of details hereinafter described, all of which contribute to produce an efficient device for this purpose.

A preferred embodiment of my invention will be particularly described in the following specification, while the broad scope 50 of the invention will be pointed out in the appended claims.

In the drawings, Figure 1 is a plan illustrating the manner of employing my invention in practice; Fig. 2 is an end elevation 55 of one of the devices and also illustrating

the special alining means; and Fig. 3 is a longitudinal section through two of the bases or guide members in which the traveler moves and illustrating how the traveler passes from one member to the other.

60

Referring more particularly to the parts, 1 represents a part of a printer's form which may comprise a plurality of interchangeable bases 2 and guide blocks 4 upon which the printing plate 3 is supported. I prefer to give the guide blocks 4 a special form and having a continuous open slot 5 passing from end to end and disposed over a channel 6 which passes completely through the base or block. Just within the slot 5 I prefer to provide guide grooves 7 which may be engaged by the sides of a traveler 8 which is adapted to travel or slide longitudinally in the slot. This traveler 8 preferably supports within the channel a rigid arbor 9 on which there is rotatably mounted a screw 10. The thread of this screw 10 engages threads 11 which are formed in the underside of the channel. On the upper side of the traveler I may provide a hook or plate engaging 80 member 12 having a pin socket 13 or other means for rotating a bevel-gear 14, said bevel-gear meshing with a second bevel-gear 15 which is rigid with the screw 10. By means of a pin wrench, the socket 13 may 85 be rotated so as to rotate the screw 10. As the screw rotates, it moves along in the threads 11 and advances the traveler.

In using the device I place several of the blocks or guide members 4 so that the channels 6 are disposed end to end and in alinement in such a way that a continuous channel and a continuous open slot are formed extending within the form, but not ex- 90

tending across the form. I form the 95 threads 11 in the bases so that the thread passes into and out of the adjacent faces at the same point, that is, in the vertical central plane which passes through the axis of the guide block. In this way the ends of 100 the blocks are interchangeable, and when the blocks are placed end to end, the threads of one block register exactly, that is, the pitch line of one thread registers with and forms a continuation of the pitch line of 105 the threads of the next block, and hence a continuous helical pitch line for the thread is formed permitting the screw 10 to pass uninterruptedly from one block into the next.

110

Instead of a plate engaging member 12 obviously the traveler 8 may carry a point or a slitter for marking proof sheets.

By arranging the guide blocks as indicated in Fig. 1, a plate 3 can be readily clamped between the plate engaging members 12 at any point in the form, and it will be seen that on account of the fact that the screw 10 is a self-locking device the members 12 will not back away from the plate when the pin wrench is removed from the socket 13. In other words, the plate can be locked in place and will remain locked.

Where it is desired to insure perfect alignment of the channels 6 and although in many cases it would be unnecessary to provide special means for insuring such an alignment, I may provide means for insuring perfect alignment consisting of side rules 16 which may be laid on one or both sides of the blocks which are alined end to end and the inner faces of these rules 16 may have pins 16a received in longitudinal grooves 17 formed in the outer sides of the blocks. These bases and blocks are all cut to standard sizes so that they can be readily alined as suggested. When these side rules are used the guide blocks are narrower, so that taken with the side rules they measure 30 the same width as one of the bases 2.

The channel formed by the blocks 4 does not pass any considerable distance under the plate 3 but only under the edges and hence the plate is well supported in printing.

35 In order to make the guide blocks reversible, it is advisable that the pitch line at the end of each block should emerge onto the end of the block in the central longitudinal plane of the block and at the same height on 40 the block.

It is understood that the embodiment of the invention which I have described above is only one of the many forms or embodiments the invention may take, and I do not 45 wish to be limited in the practice of the invention, nor in my claims to the particular embodiment described above.

What I claim is:—

1. In printers' hooks in combination, two 50 members having channels passing completely therethrough and disposed adjacent with said channels in alinement, said channels having internal threads, the pitch line of the threads of one of said channels being 55 arranged to register with and form a continuation of the pitch line of the threads of the other channel so as to form an uninterrupted continuous thread from one channel to the other, a moving part traveling in 60 said channels engaging said threads and adapted to pass from one of said members into the other, and a plate engaging member moving with said moving part and adapted to be advanced by said moving part 65 when said moving part rotates.

2. In printers' hooks in combination, two members having channels passing completely therethrough and disposed adjacent with said channels in alinement, said channels having internal threads, the pitch line 70 of the threads of one of said channels being arranged to register with and form a continuation of the pitch line of the threads of the other channel so as to form an uninterrupted continuous thread from one channel 75 to the other, a moving part traveling in said channels engaging said threads and adapted to pass from one of said members into the other, a plate engaging member moving with said moving part and adapted to be advanced by said moving part when said moving part rotates, and means for rotating said moving part from a point above said members.

3. In printers' hooks in combination, two 80 members having channels passing completely therethrough and disposed adjacent with said channels in alinement, said channels having internal threads, the threads of one of said channels being arranged to register with the threads of the other channel so as to form an uninterrupted continuous thread from one channel to the other, a screw traveling in said channels engaging said threads and adapted to pass from one 85 of said members into the other, a part moving with said screw and adapted to be advanced by said screw when said screw rotates, and means for engaging said members to maintain said channels in alinement.

4. In printers' hooks in combination, two 90 members having channels passing completely therethrough and disposed adjacent with said channels in alinement, said channels having internal threads, the threads of one of said channels being arranged to register with the threads of the other channel so as to form an uninterrupted continuous thread from one channel to the other, a screw traveling in said channels engaging 95 said threads and adapted to pass from one of said members into the other, a plate engaging part moving with said screw and adapted to be advanced by said screw when

100 said screw rotates, and a rule extending longitudinally of said members at the side thereof and engaging the same to aline said channels.

5. In combination, a block having a channel extending completely therethrough and having a continuous open slot extending completely therethrough above said channel, a traveler mounted to slide in said slot, an arbor rigidly mounted in said traveler, a screw to rotate loosely on said arbor and having a bevel-gear rigid therewith, said channel having internal threads extending completely through said member and engaging said screw, a socket rotatably mounted in the upper side of said traveler, and a bevel- 130

gear wheel rigid with said socket and engaging said first bevel-gear to rotate said screw.

6. In printers' hooks in combination, two members having channels passing completely therethrough and disposed adjacent with said channels in alinement, said channels having internal threads, the threads of one of said channels being arranged to register with the threads of the other channel so as to have an uninterrupted continuous helical pitch line from one channel to the other, a screw traveling in said channels engaging said threads and adapted to pass from one of said members into the other, a member connected with said screw and

adapted to be advanced by said screw when said screw rotates.

7. A printer's hook comprising in combination, a block, having internal threads 20 passing continuously therethrough, a screw rotatably mounted in said thread, a traveler rotatably carrying said screw and gears mounted on said traveler meshing together and held in working position by their own 25 bearings.

Signed at New York city, N. Y., this 3rd day of April, 1913.

FRANK C. LEETHEM.
